UNITED STATES PATENT OFFICE.

JOHN MASON MILLER, OF DUNBAR, PENNSYLVANIA.

CAR-BRAKE.

1,249,986.

Specification of Letters Patent. Patented Dec. 11, 1917.

Application filed April 19, 1917. Serial No. 163,198.

To all whom it may concern:

Be it known that I, JOHN M. MILLER, a citizen of the United States, residing at Dunbar, in the county of Fayette and State 5 of Pennsylvania, have invented a new and useful Car-Brake, of which the following is a specification.

This invention has reference to car brakes, and its object is to provide a means which 10 will automatically stop and hold cars being hauled up grade when for any reason the cars start down grade otherwise uncontrolled.

The invention is particularly applicable to coal and other cars used in mines and on 15 inclines where the cars sometimes break away and rapidly descend in the absence of automatic means for arresting the down run of the cars.

The invention comprises a grip or clutch 20 member adapted to travel along a rail of the track along which the car is moving, or two of such clutch or grip members may be employed on the two rails. The grip members are arranged in trailing relation to the car 25 and are connected together, while a wheel-engaging member for each grip member is provided and so arranged that in the event of the car moving rapidly down grade the wheel-engaging member is actuated by the 30 wheel in a manner to twist or turn the grip member so as to clamp itself to the rail and thereby hold the car against further downward progress. The grip members are supported upon runners capable of traveling 35 along the ties of the track, so as to support the grip members, while flexible strands are provided to hold the parts to the car when the car is progressing up grade and the grip members are in trailing relation to the car.

40 The invention will be best understood from a consideration of the following detailed description, taken in connection with the accompanying drawings forming part of this specification, with the further understanding that while the drawings show a 45 practical form of the invention, the latter is not confined to any strict conformity with the showing of the drawings, but may be changed and modified so long as such changes 50 and modifications come within the scope of the appended claims.

In the drawings:—

Figure 1 is a plan view of an embodiment of the invention.

55 Fig. 2 is an end elevation showing the track rails in cross-section.

Fig. 3 is a central longitudinal section of the structure shown in Fig. 1.

Fig. 4 is a detail view of one of the gripping members applied to a rail. 60

Referring to the drawings there are shown track rails 1 and ties 2 constituting a track. There is also shown a beam 3 and wheels 4 which may be taken as indicative of a car truck. 65

The car brake structure comprises a drag composed of two blocks 5, each with an arm 6 fast thereto, the blocks 5 being formed with shoes 7 adapted to the treads of the wheels 4. The arms 6 are joined together 70 near the ends carrying the blocks 5 by a cross bar 8 secured by bolts 9, or in any other suitable manner, to the arms 6, so that the blocks 5 are held in such spaced relation that they will be readily engaged by or engage 75 the wheels 4 at the treads thereof. That end of each arm 6 remote from the block 5 is made fast by a bolt 10 or otherwise to one end of another arm 11, which at the end remote from the bolt 10 is formed into a 80 gripping or clamping head 12. The arms 11 near the heads 12 are joined by a bar 13, thus spacing the heads 12 so as to properly span the track. Each head 12 is formed with two opposed jaws 14 having lips 15 po- 85 sitioned to underride the tread of a rail 1 when the head 12 is resting on the rail. When the head 12 with its arm 11 is sub-stantially perpendicular to the length of the rail the head 12 is loose on the rail and will 90 slide readily therealong. When, however, the head 12 is turned at an angle to the length of the rail with the angle sufficient the lips 15 engage under the tread of the rail, while the sides of the jaws 14 engage 95 opposite sides of the tread of the rail and thereby clamp the head 12 to the rail, so that it is held fast thereto. The arms 11 adjacent to the heads 12 and the arms 6 ad- jacent to the blocks 5 are connected by 100 chains 16, or in any other suitable manner limiting the movements of the arms apart and not interfering with the movement of the arms toward each other. The bar 8 is secured to the cross beam 3 by chains 17 105 or other suitable connections serving to draw the drag structure along with the car, but not interfering with the approach of the car to the drag structure in the event of the car backing, as would be the case where the 110 track structure is in trailing relation to the car while the car is climbing a grade and for

some reason the car suddenly moves down grade.

In order to support the arms 6 and 11, shoes 18 are provided. These shoes may be 5 carried by the arms 11 or other parts of the structure, and have rounded extremities 19 so as to readily travel along the ties 2 without interference.

When the car is moving up grade the 10 tendency of the car is to move away from the drag structure. The chains 17 are then taut with their slack taken up, and hence the shoes 7 may be at some little distance from the wheels 4. Also, the movement of the 15 drag along the rails tends to move the heads 12 away from the shoes 7, whereupon this movement continues until the chains 16 also become taut. Under these conditions the arms 11 travel along the rails in a position 20 which may be perpendicular to or nearly perpendicular to the length of the rails. When the parts are thus positioned the heads 12 are loose with respect to the rails and out of gripping relation thereto. Suppose 25 that for some reason, such as a breakage of connection, the car should start down hill when on a grade, the drag being loosely coupled to the car does not participate in the down movement as rapidly as the car 30 and consequently the car wheels engage the shoes 7 and then push these along down hill with the car. This causes the arms 6 to move the arms 11 until the jaws 14 engage the sides of the rail, whereupon the head 35 12 becomes cramped upon the rail, thus arresting movement of both the arms 11 and 6 and with the wheels 4 pressing against the shoes 7 the drag becomes securely fast to the rails, thus stopping further down hill movement of the car. The weight of the car only 40 tends to cramp the heads 12 harder against the rails, and hence the car is effectively locked or braked against further movement. When the car starts up hill, or is traveling 45 up hill or along a level, the heads 12 loosen from the rails and the arms 6 and 11, which are in acute angular relation in the holding position of the drag, assume a less acute angular relation, so that the arms 11 are about 50 perpendicular to the rails and the heads 12 are wholly out of gripping relation to the rails.

Tracks frequently contain guard rails and frogs and in order to avoid interference 55 with such structures the jaws 14 have outstanding horns 20 projecting away from the rails, thus enabling the clamp head 12 to be guided up over the guard rails or frogs.

In inclines or other tracks designed to 60 accommodate coal cars in the coal regions, the space between the rails is sometimes occupied by rollers and other devices. Under such circumstances the runners or shoes 18 may be otherwise located than as shown in 65 the drawings and the clamp or cramp heads

may be so situated as to avoid interference with structures permanently located between the track rails.

The blocks 5 may each be made long enough to have their lower ends rest upon 70 the tread portions of the rails so that the chains 17 may not be subjected to excessive strains liable to break them. Also the lower ends of the blocks may be formed to partially straddle the treads of the rails and 75 thus prevent side displacement of the blocks.

What is claimed is:—

1. A car brake comprising a drag structure with means for securing it in trailing relation to the car, said drag structure having rail gripping devices, each in loose straddling relation to the tread of the rail, and actuating devices for the rail gripping devices located in the path of the car to be engaged thereby and move the acute angular gripping devices into gripping relation to the rails on travel of the car toward the drag. 80

2. A car brake comprising connected arms each terminating in a head in position to 90 be engaged by a car wheel, and other arms jointed to the first arms and terminating in clamping heads for gripping the tread portions of rails, connections between the arms for spacing them with relation to the 95 rails of a track, and other connections for securing the arms to a car truck.

3. A car brake structure, comprising arms each having an end arranged in the path of a car wheel with the arms connected together and spaced apart to be in the path of respective car wheels, other arms one for each of the first-named arms and joined thereto, the second arms being connected together and spaced apart similarly to the 100 first-named arms and each terminating in a cramping head adapted to embrace the tread portion of a respective rail, and flexible connections between the head portions of the arms and also between the arms and 105 a car truck.

4. A car brake structure, comprising arms each having an end arranged in the path of a car wheel with the arms connected together and spaced apart to be in the path 110 of respective car wheels, other arms one for each of the first-named arms and joined thereto, the second arms being connected together and spaced apart similarly to the first-named arms and each terminating in 115 a cramping head adapted to embrace the tread portion of a respective rail, and flexible connections between the head portions of the arms and also between the arms and a car truck, the structure also being provided with runners arranged to travel along the ties of a track and support the arms in 120 operative relation to the rails.

5. In a car brake structure, an arm having at one end means for engagement with a 130

car wheel, another arm jointed to the first arm and provided with a head having jaws for straddling and cramping the tread portion of a rail, and means for connecting the 5 jointed arms to a car truck with the head of the first-named arm in position to be engaged by a car wheel.

6. In a car brake structure, a jointed rail gripping member having means for connecting it to a car, with the gripping portion of the gripping means in the form of a head with opposed jaws for engaging opposite sides of the tread portion of the rail, the jaws having outstanding horns for engaging parts of the track in the path of the 10 head and lifting the latter over said parts.

15 Copies of this patent may be obtained for five cents each, by addressing the "Commissioner of Patents, Washington, D. C."

7. In a car brake, a jointed gripping structure having one end provided with a gripping head adapted to engage and grip a rail, and supporting shoes for the gripping structure positioned with relation to said gripping structure to travel upon the ties of a track and uphold the gripping structure in operative relation with the rails of the track. 20

In testimony, that I claim the foregoing 25 as my own, I have hereto affixed my signature in the presence of two witnesses.

JOHN MASON MILLER.
